UNITED STATES PATENT OFFICE.

PAUL VIERKÖTTER, OF MUNICH, GERMANY.

FLASH-LIGHT LAMP.

Application filed December 29, 1926, Serial No. 157,844, and in Germany August 15, 1925.

With all known flash-light lamps, the explosive charge burns with an open flame which necessitates the provision of special safety devices in order to prevent fires. If powder mixtures are used, they must be prepared immediately before use as the finished mixture soon loses its effectiveness in the air. Combustion takes place in an explosive manner with more or less noise which is apt to startle the observers. The flame is not uniform, and it grows so big that it is difficult or even impossible to distribute the light by means of a diaphragm or a reflector. The cloud of smoke and vapor arising during the combustion becomes distributed about the room and impairs visibility, so that it is nearly impossible to make several exposures one after another in a small closed room. The combustion gases are, besides, harmful to the respiratory organs.

The object of the present invention is to avoid the drawbacks from which the flash-light lamps with open flame suffer, and for this purpose the flash-light substance or charge is enclosed in a transparent hollow body which is practically completely exhausted of air, or at least partly so. The combustion takes place, therefore, in a closed space and there is no longer any danger whatever of fires. Bursting of the lamp in consequence of the combustion of the flash-light substance cannot occur because there is either practically no air at all within the lamp, or its amount is so small that no heating and expansion worth mentioning are caused. The flame is restricted to the narrow space within the lamp; and this being so, there is produced a kind of globe or ball of light of very great illuminating intensity, the light rays from which can be directed or reflected to any desired place by means of a screen attached directly to the lamp. The detonating noise is obviated, as sound is not propagated in vacuo. The combustion gases cannot escape from the lamp but precipitate on the inner wall of the same, and it is, therefore, possible to make use of as many flash-light exposures as desired, one after another, without impairing the transparency of the air and acting detrimentally upon the respiratory organs.

If a flash-light powder is employed, there is no danger of its effectiveness decreasing, as the very small amount of air still contained in the lamp is of no consequence. It is a matter of course that only such sub-

stances can be used for flash-light purposes in vacuo as can be admixed with an oxygen-producing substance, such as manganese peroxide, ammonium nitrate or the like. 60 The manner in which combustion occurs can be influenced by the introduction of a rarefied gas in such a way that explosions do not take place and that combustion is promoted. The ignition of the charge can be 65 effected in several ways, for instance chemically or mechanically or by heating. Employing electricity for this purpose is particularly practical, in that the igniter can be used directly or indirectly in the form of a 70 wire, band, spiral, tube, etc., as a part of the electric conductor (resistance ignition, arc-ignition, induction ignition).

The invention is illustrated diagrammatically and by way of example in the accompanying drawing in which Figure 1 is an axial section through a flash-light lamp designed according to this invention, and Figure 2 is a similar representation showing a modification, the difference residing chiefly 80 in that in Fig. 1 the lamp has one flash-light charge and in Fig. 2 two such charges.

The improved lamp resembles an ordinary electric incandescent lamp. The fitting 1 carries a glass bulb 2, the lower end 85 of which is made integral with an upwardly directed projection 3 through which pass conducting wires 4. The outer end of one wire is conductively connected with the metallic fitting 1 at the point 5, and that of 90 the other wire with the metallic contact disk 6 which is insulated from said fitting. 7 is a small tube enclosed air-tight in the projection 3 and serving for exhausting the bulb, and 8 is an asbestos disk which is 95 fixed to said projection by means of pins 9. The asbestos disk 8 is disposed within and firmly connected to a glass cylinder 10 that extends downwardly into the neck of the bulb 2 so that its lower portion surrounds the head of the projection 3 and the free portions of the wires 4. The upper portion of the cylinder 10 supports within it a small casing 11 holding the flash-light powder 12; and this casing must be so constructed as to offer the lowest possible resistance to the gas pressure that arises 100 instantly after the ignition of the charge 12, for which purpose the annular side wall of the casing, the closing disk 13 and the bottom disk 14 are merely glued together or 105 connected in a similar manner. The parts

forming the casing or receptacle 11 consist preferably of asbestos or glass and are as thin as possible. The disk 13 bears upon the rim of the glass cylinder 10 and is cemented or similarly fastened thereto. In order to prevent the lamp from being blackened when the flash-light powder is ignited, inorganic substances, such as a mixture of water-glass and fluor-spar, are used 10 to form the cementing medium.

In the flash-light powder or charge 12 is embedded a helically wound ignition wire 15 which is clamped fast between the side wall and the top and bottom disks 13 and 15 14 of the receptacle 11, and the ends of which extend down between the cylinder 10 and the asbestos disk 8, below which they are connected with the current-carrying wires 4.

20 When the lamp is screwed into a socket and the current is switched on, the flash-light charge is exploded instantaneously by the glowing spiral 15. The receptacle 11, 13, 14 is destroyed at once as it presents 25 practically no resistance to the gases generated at the moment of the explosion. The burning gases can spread freely to all sides and form, as it were, an intensely luminous ball. As the bulb is evacuated, it is prevented 30 from being destroyed by an increase of pressure resulting from the gases enclosed within it.

The glass projection 3 and the current-supplying wires 4 are protected by the lower portion of the glass cylinder 10 so that 35 said projection is prevented from being shattered, and said wires from being short-circuited, by the flame. As the flame arising when the combustion takes place forms 40 a conductor for the current, the amount of current increases in such a measure that the spiral 15 melts through, whereby the circuit is broken automatically and the fuses in the circuit are prevented from disruption. In order to obtain an instantaneous 45 ignition the ignition wire or spiral must be able to stand as high a temperature as possible before melting; suitable materials for it are iron, tungsten, tantalum and molybdenum.

The effectiveness of the lamp, as described, depends upon the maintenance of the vacuum, and means must, therefore, be provided by which the circuit is broken 55 automatically if it should happen that the vacuum is destroyed from any cause. In the example shown a capillary tube 16 is inserted into the asbestos disk 8. This tube is closed at its upper end and open at its lower end, and the uppermost portion of the interior of the tube is separated from the portion below by a drop 17 of mercury, whereby a certain small amount of air is kept enclosed in the aforesaid portion of 60 the tube 16. The current-supplying wire

4 which is located on the corresponding side of the lamp extends into the open end of the capillary tube, as does also the adjacent end of the wire 15, but the two wire ends do not contact with each other, as shown. 70 When the bulb is being evacuated the mercury drop is drawn downwards within the capillary tube and contacts finally with the wire ends mentioned, whereby these are conductively connected with each other. If 75 the lamp should become leaky, the mercury drop will be forced upwardly in the tube away from the wire ends in question by the pressure of the in-coming air, so that the circuit is broken and the flash-light charge 80 cannot be exploded.

When a flash-light charge has been exploded, the lamp will be ready for the explosion of another charge as soon as the combustion gases have condensed, so that it 85 is possible to employ a lamp for a succession of flash-light exposures. In other words: there may be made lamps containing a plurality of flash-light charges, but then provision must be made for preventing the other charge or charges from exploding when the first charge is ignited. 90

A flash-light lamp answering this requirement and intended for two exposures is illustrated in Fig. 2. 18 and 19 indicate the two flash-light charges which are separated from each other by a mica wall 20. Each charge is carried by a supporting device similar to that described in connection with Fig. 1 (glass cylinder, asbestos disk, and so on); 100 and these two devices are supported by a wire bow 23 serving also as common current supplying member for one end of each of the two ignition spirals 21 and 22. The other ends of the spirals are connected with wires 24 and 25 terminating outside the lamp, at the foot of the fitting 27, at two contact disks 28 and 29 which are insulated from each other by an insulating disk 30. The common bow 23 is conductively connected with the fitting 27 at the point 26. There are two circuits: the first: 27, 26, 23, 22, 25, 28; the second: 27, 26, 21, 24, 29. This latter circuit is used first. When the charge 18 has been ignited, the combustion gases have condensed, and the lamp has cooled down, the lamp is unscrewed from the socket (not shown) and the contact disk 29 and the insulating disk 30 are torn off, whereafter the lamp is again screwed into the socket so that 110 now the other circuit can be closed in order to explode the other flash-light charge. 115

As the combustion takes place in the closed bulb 2 and the size of the flame is, therefore, predetermined, it is possible to shut off the rays in one direction and direct them by reflection in another direction, for instance, in such a way that the light illuminates the object subjected to the exposure, but does not illuminate any other part of the room where 120 125 130

the exposure is made. For these purposes the lamp is provided with a screen 31 (Figs. 1 and 2) which is attached to the fitting 1 (Fig. 1) or 27 (Fig. 2) by means of a ring 32 that is shoved over the respective fitting and is clamped fast, after having been properly adjusted, between the fitting and the socket when the fitting is screwed home in the socket.

10 I claim as my invention:—

1. A flash-light lamp, comprising, in combination, a hollow, transparent body which is at least partially evacuated, a carrier for a flash-light charge enclosed in said body, and means for exploding said charge within the said body.

2. A flash-light lamp, comprising, in combination, a hollow, transparent body, filled with a gas, the pressure of which is below that of the atmosphere, a carrier for a flash-light charge enclosed in said body, and means for exploding said charge within the said body.

3. A flash-light lamp, comprising, in combination, a glass bulb which is at least partially evacuated, a fitting firmly connected with one end of said bulb, a projection integral with the bulb and extending centrally from said fitting into the bulb, contact members at said fitting, conducting wires extending from said contact members through said projection into said bulb, a carrier for a flash-light charge enclosed in the bulb, and electric means for exploding said charge within the bulb, said exploding means being conductively connected with said wires.

4. A flash-light lamp, comprising, in combination, a glass bulb which is at least partially evacuated, a fitting firmly connected with one end of said bulb, a projection integral with the bulb and extending centrally from said fitting into the bulb, an exhausting tube extending through said projection and sealed therein, contact members at said fitting, conducting wires extending from said contact members through said projection into the said bulb, a carrier for a flash-light charge enclosed in the bulb, and electric means for exploding said charge within the bulb, said exploding means being conductively connected with said wires.

5. A flash-light lamp, comprising, in combination, a glass bulb which is at least partially evacuated, a fitting firmly connected with one end of said bulb, a projection integral with the bulb and extending centrally from said fitting into the bulb, contact members at said fitting, conducting wires extending from said contact members through said projection into the said bulb, a carrier for a flash-light charge enclosed in the bulb, a disk connected to said projection, a glass tube enclosing said disk and supporting said carrier, and electric means for exploding said charge, the current-supplying wires

which connect the exploding means with the said contact members being clamped between said disk and said glass tube.

6. A flash-light lamp, comprising, in combination, a hollow, transparent body which is at least partially evacuated, a receptacle adapted to contain a flash-light charge and consisting of a material presenting practically no resistance to the explosion gases, and means for exploding said charge within the said body.

7. A flash-light lamp, comprising, in combination, a hollow transparent body which is at least partially evacuated, a receptacle adapted to contain a flash-light charge and comprising an annular body and a bottom disk and a top disk, and means for exploding said charge within the said body.

8. A flash-light lamp, comprising, in combination, a glass bulb which is at least partially evacuated, a fitting firmly connected with one end of said bulb, a projection integral with the bulb and extending centrally from said fitting into the bulb, contact members at said fitting, conducting wires extending from said contact members through said projection into the said bulb, a receptacle adapted to contain a flash-light charge and comprising an annular body and top and bottom disks, a glass cylinder enclosing said receptacle and cemented at its upper end to the rim of the top disk, and means for exploding said charge within the said body.

9. A flash-light lamp, comprising, in combination, a hollow, transparent body which is at least partially evacuated, a receptacle adapted to contain a flash-light charge and comprising an annular body and a bottom disk and a top disk, and electric means for exploding said charge and including current-supplying wires one of which is clamped fast between the annular body and the top and bottom disks of the said receptacle.

10. A flash-light lamp, comprising, in combination, a glass bulb which is at least partially evacuated, a fitting firmly connected with one end of said bulb, a projection integral with the bulb and extending centrally from said fitting into the bulb, contact members at said fitting, conducting wires extending from said contact members through said projection into the said bulb, a carrier for a flash-light charge enclosed in the bulb, and an ignition wire embedded in said charge and consisting of a metal having a high fusing point, the sectional area of said wire being such that it melts through when the charge is ignited and exploded.

11. A flash-light lamp, comprising, in combination, a glass bulb which is at least partially evacuated, a fitting firmly connected with one end of said bulb, a projection integral with the bulb and extending

- centrally from said fitting into the bulb, contact members at said fitting, conducting wires extending from said contact members through said projection into the said bulb, 5 a carrier for a flash-light charge enclosed in the bulb, a disk connected to said projection, a capillary tube extending through said disk and being open at its lower end and closed at its upper end, a drop of mercury 10 enclosed in said tube and enclosing in turn a small volume of air between it and said closed tube end, a glass tube enclosing said disk and supporting said carrier, and electric means for exploding said charge, one 15 of the current-supplying wires connecting said exploding means with the said contact members being cut through and the ends at the place of cutting being inserted into the open end of the said capillary tube.
- 20 12. A flash-light lamp, comprising, in combination, a glass bulb which is at least partially evacuated, a fitting firmly connected with one end of said bulb, a projection integral with the bulb and extending centrally from said fitting into the bulb, contact members at said fitting, conducting wires extending from said contact members through said projection into the said bulb, a plurality of carriers for flash-light charges enclosed in the bulb, screening means between the individual carriers, electric means for exploding said charges one after another, a common conducting wire connecting all the charges with said fitting, a separate contact individual to each charge and associated with the fitting, and individual conducting wires connecting said separate contacts with the respective charges. 25
- 30 13. A flash-light lamp, comprising, in combination, a hollow, transparent body which is at least partially evacuated, a carrier for a flash-light charge enclosed in said body, means for exploding said charge within the said body, and a turnable screen attached to the lamp. 35
- 40 In testimony whereof I have affixed my signature.
- 45 PAUL VIERKÖTTER.
